(57) **CLAIM**

The ornamental design for the “swivel rocker”, as shown and described.

DESCRIPTION

FIG. 1 is a front elevational view of a chaise showing my design.

FIG. 2 is a rear elevational view thereof;

FIG. 3 is a top plan view thereof;

FIG. 4 is a bottom plan view thereof;

FIG. 5 is a right side elevational view thereof; the left side elevational view being the mirror image thereof; and,

FIG. 6 is a perspective view thereof.

The fragmented weave pattern shown in FIGS. 1, 2, 5 and 6 is understood to represent the weave pattern and would be continuous throughout the circumscribed area.
